[57] **CLAIM**

The ornamental design for a tourniquet and pressure applying device, as shown and described.

DESCRIPTION

FIG. 1 is a top plan view of a tourniquet and pressure applying device, showing my new design;

FIG. 2 is a side elevation thereof;

FIG. 3 is a bottom plan view thereof;

FIG. 4 is a left end elevation thereof;

FIG. 5 is a right end elevation thereof;

FIG. 6 is a perspective view thereof; and

FIG. 7 is a perspective view taken in an alternate position of FIG. 6.

The broken lines illustrating the human arm are shown for illustrative purposes only.
